United States Patent Office

Des. 201,821
Patented Aug. 3, 1965

201,821

RING

Louis Solomon, Chicago, Ill.

Filed Feb. 26, 1964, Ser. No. 78,790

Term of patent 14 years

(Cl. D45—10)

Fig. 1.

Fig. 4.

Fig. 2.

Fig. 5.

Fig. 3.

Fig. 6.

FIG. 1 is a top plan view of a ring embodying my new design;

FIG. 2 is a front elevational view;

FIG. 3 is a rear elevational view;

FIG. 4 is a right side view; and

FIG. 5 is a left side view of the same.

FIG. 6 is a partial sectional view taken on line 6—6 of FIG. 3.

The essential features of the design reside in the full line portions on the drawing.

I claim:

The ornamental design for a ring, substantially as shown and described.
